UNITED STATES PATENT OFFICE.

RICHARD HOELEMANN, OF BROOKLYN, NEW YORK.

SAFETY ATTACHMENT FOR POWER-PRESSES.

1,102,509.

Specification of Letters Patent. Patented July 7, 1914.

Application filed November 1, 1913. Serial No. 798,639.

To all whom it may concern:

Be it known that I, RICHARD HOELEMANN, a citizen of the United States, and residing at Brooklyn, Greater Ridgewood, in the county of Kings and State of New York, have invented certain new and useful Improvements in Safety Attachments for Power-PresSES, of which the following is a specification, such as will enable those skilled in the art to which it appertains to make and use the same.

This invention relates to ordinary power presses and particularly to safety devices for apparatus of this class, and the object thereof is to provide an ordinary power press with an improved attachment designed to prevent injury to the fingers or hands of an operator by reason of carelessness or indifference in the operation of the machine. The invention is fully disclosed in the following specification of which the accompanying drawing forms a part, in which the separate parts of my improvement are designated by suitable reference characters in each of the views, and in which;

Figure 1 is a side view of a part of a power press showing my improvement applied thereto; Fig. 2 a cross section on the line 2—2 of Fig. 1; Fig. 3 a partial section on the line 3—3 of Fig. 1, and on an enlarged scale, and; Fig. 4 a partial section on the line 4—4 of Fig. 2, and on an enlarged scale.

In the drawing forming part of this specification, I have shown the main parts of the frame of an ordinary power press comprising a front table portion *a*, vertical and parallel side back frame members *a*², the die bed *b*, the vertically movable plunger *c* and the die *d* connected with said plunger. I have also indicated at *e*, the clutch head at the top of the machine, said clutch being detached in the accompanying drawing, and at *f*, I have shown the usual vertically movable clutch rod which, in the use of the machine, is operated by a foot lever or pedal, not shown, to throw the machine into operation, the upper end portion of said clutch rod being shown at *f*² and in engagement with the clutch head *e*, all these parts being of the usual construction, and forming no part of my invention.

In carrying my invention into effect, I mount in the vertical frame members *a*², a

horizontal shaft *g*, one end of which is provided with an arm *g*² rigidly secured thereto, and secured to the corresponding frame member *a*² is a bracket arm *h* having an outwardly curved head *h*² through which is passed a vertically arranged adjusting screw *h*³ adapted to limit the upward movement of the arm *g*², and secured to said arm *g*² is a spiral spring *g*³ which is secured to the corresponding frame member *a*² at *g*⁴, and which serves to raise the arm *g*² and to turn the shaft *g* in the backward direction, and is secured to the arm *g*² by an eye-bolt or screw *g*⁵.

Mounted on the clutch rod *f* above and forwardly of the shaft *g* and rearwardly of the bracket arm *h* is a split block *i* which serves to depress the arm *g*² in the downward movement of the clutch rod *f* and to turn the shaft *g* in a forward direction. Mounted on the shaft *g* between the frame members *a*² is a split block *j* having forwardly directed jaws *j*² between which is pivoted an arm *k*. In the form of construction shown, a bolt *k*² is passed through the end of the arm *k* and through the jaws *j*², and one of the jaws *j*² and the arm *k* are provided respectively, at one side, with jaws *j*³ and *k*³, and set screws *m* are passed through the jaw *k*³ and adapted to bear on the jaw *j*³, and by adjusting the screws *m*, the arm *k* may be turned vertically on the bolt *k*², into any desired position and secured therein. In power presses of the class to which my invention relates, the die beds *b* are of different vertical thicknesses, and this renders necessary, the vertical adjustment of the guard arm or arms so as to accommodate the attachment to different presses. The split block *f* is also provided with projecting jaws *j*⁴ through which are passed bolts *j*⁵, and by means of this construction, the block *j* may be adjusted longitudinally of the shaft *g* and is secured thereto to prevent its rotation thereon, by a set screw *j*⁶ or in any other way.

The forward end of the arm *k* is provided with a bracket plate *n*, to which is adjustably secured a plate *o* provided with a forwardly directed arm *o*² having a loop-shaped front end *o*³ through which the die *d* is adapted to operate. One of the parts *n*—*o*, preferably *o*, is provided with longitudinal

slots p through which are passed bolts p^2 by which the parts n and o are connected, and by means of this construction, the part o may be adjusted longitudinally of the 5 part n .

The normal position of the parts, when the machine is not in operation, is that shown in Fig. 1, in which the arms k and o^2 are raised above the die bed b . In the operation of starting the press, the clutch rod f is depressed, in the usual manner, and this 10 throws the arms k and o^2 into the position shown in dotted lines in Fig. 1, in which the arm o^2 rests on the die bed b , and the plunger c operates in the usual manner. The accidents hereinbefore referred to usually occur by reason of the operator carelessly 15 placing his hand or fingers on the die bed b at the time the press is thrown into operation, or by the operator failing to remove his hand or fingers from the die bed at the time 20 the press is thrown into operation. With my improvement however, the descent of the arms k and o^2 on the die bed occurs before 25 the downward movement of the plunger c , and this warns the operator whose hand or fingers will be struck by the arm o^2 , and stops the machine until they are removed from the die block.

30 My invention does not in any way affect the construction and operation of the press and consists only of the attachment herein shown and described.

My invention is also not limited to any 35 particular means for, or method of connecting the arm k with the shaft g , nor of connecting the arm o^2 with the arm k , nor is it necessarily limited to the formation of the arm k and the block j of different parts, nor 40 to the formation of the arms k and o^2 of different parts, but I prefer to make the arms k and o^2 of different parts so as to provide for the adjustment of the arm o^2 , and other changes in and modifications of the 45 various parts of my improved safety attachment for power presses, as herein shown and described may be made, within the scope of the appended claims, without departing

from the spirit of my invention or sacrificing its advantages.

Having fully described my invention, what I claim as new and desire to secure by Letters Patent is;—

1. In a power press of the usual construction and involving the usual pedal operated clutch rod, a safety attachment comprising a shaft mounted transversely of and rearwardly of the die bed of the press, a forwardly directed guard arm connected with said shaft, automatic means for turning said shaft so as to raise said guard arm, and means for turning said shaft to depress said guard arm onto the die bed, comprising a stop arm connected with the shaft and a part 60 connected with the clutch rod and operating in connection with said stop arm, and a stop device connected with the frame for limiting the upward movement of said stop arm and the turning of the shaft to raise the 65 guard arm.

2. In a power press of the usual construction and involving the usual pedal operated clutch rod, a safety attachment comprising a horizontal shaft mounted rearwardly of the die bed of the press, a forwardly directed 70 guard arm connected with said shaft and provided at its front end with a guard, a spring for turning said shaft so as to raise the guard arm, a stop arm connected with said shaft and a stop connected with the 75 frame of the press and in connection with which the stop arm operates to limit the said movement of said shaft, and a part connected with the clutch rod and operating in connection with said stop arm member 80 to turn said shaft so as to depress said guard arm onto the die bed of the press.

In testimony that I claim the foregoing as my invention I have signed my name in presence of the subscribing witnesses this 90 31st day of October, 1913.

RICHARD HOELEMANN.
